Application March 16, 1954, Serial No. 29,548

Term of patent 14 years

(Cl. D58—6)

FIG. 1.

FIG. 2.

FIG. 4.

FIG. 3.

FIG. 5.

To all whom it may concern:

Be it known that I, Robert Olifiers, a citizen of the United States, residing at Scarsdale, in the county of Westchester and State of New York, have invented a new, original, and ornamental Design for a Bottle, of which the following is a specification, reference being had to the accompanying drawing, forming part thereof.

Fig. 1 is a front elevational view of a bottle showing my new design;

Fig. 2 is a side elevational view thereof;

Fig. 3 is a rear elevational view thereof;

Fig. 4 is a top plan view thereof; and

Fig. 5 is a horizontal section thereof, along the line 5—5 of Fig. 1.

The horizontal and vertical lines applied to the surfaces of the cap portion represent gold color although any

other color may be substituted without changing the ornamental design.

I claim:

The ornamental design for a bottle, substantially as shown and described.
